Geo. P. Kimmel. ATTORNEY.

UNITED STATES PATENT OFFICE.

WILLIAM D. STACEY, OF VANCOUVER, WASHINGTON.

FUEL BURNER.

Application filed March 6, 1925. Serial No. 13,577.

To all whom it may concern:

Be it known that I, WILLIAM D. STACEY, a citizen of Great Britain, residing at Vancouver, in the county of Clarke and State of Washington, have invented certain new and useful Improvements in Fuel Burners, of which the following is a specification.

This invention relates to fuel burners and pertains particularly to the class of hydrocarbon burners.

The primary object of this invention is the provision, in a manner as hereinafter set forth, of a hydrocarbon burner designed to use steam in connection with the hydrocarbon, and further designed to atomize the fuel and the steam to form a perfectly combustible fuel.

Another object of the invention is the provision, in a manner as hereinafter set forth, of a hydrocarbon oil burner having a plurality of atomizers in the body thereof whereby a perfectly mixed spray of the oil and steam will be discharged from the burner ports for proper combustion.

The invention contemplates the provision of a circular cast body having a pair of superposed chambers in the central portion thereof, the upper chamber being of materially greater diameter than the lower chamber. Each chamber has an inlet port leading thereto. Extending downwardly from the floor of the chamber of greater diameter about the wall thereof is a series of passages which extend downwardly to a point approximately in alignment with the floor of the lower chamber whereupon the passages turn at right angles and extend outwardly radially of the body opening upon the side thereof. Extending radially from the lower chamber is a series of relatively narrow passages each one of which opens into the lower end of one of said vertical passages. These narrow passages atomize steam forced therethrough from the smaller chamber to thoroughly mix with oil drawn from the upper chamber through the vertical passages, the mixture burning at the outer ends of the passages which open upon the outside of the body.

A further and final object of the invention is the provision, in a manner as hereinafter set forth, of a hydrocarbon oil burner of simple construction, highly efficient, and inexpensive to cast and set up.

The invention will be best understood from a consideration of the following de-

tailed description taken in connection with the accompanying drawing forming a part of this specification, with the understanding that the invention is not confined to any strict conformity with the showing of the drawing, but may be changed and modified so long as such changes and modifications mark no material departure from the salient features of the invention, as expressed in the appended claims.

In the drawings:—

Fig. 1 is a vertical section through the device embodying this invention and through a portion of an attached fuel oil and steam inlet pipes.

Fig. 2 is the horizontal section taken upon the line 2—2 of Fig. 1.

Fig. 3 is a vertical section taken upon the line 3—3 of Fig. 1.

Fig. 4 is a horizontal section taken upon the line 4—4 of Fig. 1.

Referring now to the drawings in detail wherein like numerals of reference indicate corresponding parts throughout the several views, there is indicated generally by the numeral 1 the body of the device embodying this invention. This body may be formed of cast metal and though the drawing shows the same as of circular contour, it is to be understood that applicant does not limit himself to this shape for the body may be cast in any desired shape without altering the effectiveness of the burner.

Upon the top of the body 1 there is cast the substantially semi-circular boss 2, which extends from one side of the casting to the central portion thereof as shown in Fig. 1, and oil inlet passage 3 is formed through the longitudinal center of this boss and turns downwardly as at right angles 4 where it opens into the top of the upper one of a pair of superposed chambers 5 and 6 respectively. The chamber 5 is of materially greater diameter than the chamber 6 as clearly shown in Fig. 1, and this chamber constitutes what may be termed an oil manifold. The body 1 has formed therein the steam inlet passage 7 which is here shown beneath and parallel with the passage 3 and this passage 7 is materially constricted as at 8 as the chamber 6 is considerably less in height than the diameter of the inlet passage 7.

The outer portion of each of the passages 3 and 7 is interiorly threaded as at 9 to receive the threaded ends of the oil and steam

pipes 10 and 11 respectively. The steam pipe is of less diameter than the oil pipe as shown in Fig. 1.

Extending downwardly from the floor of the chamber 5 about the wall thereof, is a series of spaced passages 12 which extend downwardly to a point substantially in a plane with the floor of the chamber 6. These vertical passages 12 are shown in Fig. 2 as extending throughout one-half only of the circumference of the chamber 5, but it is to be understood that a larger series may be employed than that here shown.

Extending radially from the lower chamber 6 and opening thereinto through the wall thereof is a series of atomizer tubes or passages 13, each one of these passages opening into the lower end of one of the vertical passages 12.

Extending radially through the body 1 from the lower end of and at right angles to each of the vertical tubes 12 is a burner tube 14, the mouth 15 of each of which opens on the outside of the body 1.

As before stated, the passages 12, 13 and 14 are shown as extending throughout one-half only of the circumference of the body 1, but it is of course apparent that the same may be increased or decreased in number to give a blaze of greater or smaller spread. This can be accomplished equally as well by a burner of a contour different from that shown in the drawings and applicant does not limit himself to a burner of the contour shown.

From the foregoing description it will be seen that when the burner is in use, steam entering the chamber 6 under pressure and forcing its way through the narrow passages or atomizer tubes 13 into the outlet burner passages 14, will create a suction or vacuum in the chamber 5 and tubes 12 thereby drawing fuel oil thereinto through the pipe 3 where the same will be atomized with the steam in its passage through the tube 14 and a complete combustion of the fuel mixture will be had at the mouth 15 of the burner passages. Suitable valves may be placed in the pipe lines 10 and 11 and when the oil supply has been once properly regulated to produce the proper mixture with the steam, the steam pipe valve need be the only one to

be regulated for when the flow of steam through the atomizer tubes ceases upon the closing of the steam pipe line 11, the suction in the chamber 5 will be stopped and the oil will cease to flow.

From the foregoing description it will be readily seen that a simple and effective oil burner has been perfected which will thoroughly atomize the fuel to produce a mixture which will burn without carbon deposit.

Having thus described my invention what I claim is:—

1. A hydrocarbon burner of the character set forth, comprising a body having a pair of superposed chambers formed therein constituting oil and steam chambers, means to provide an inlet for said upper chamber entering through the top thereof, means to provide an inlet for the lower chamber entering through the side thereof, said lower chamber being materially smaller than said upper chamber and having the inlet thereto constricted, said upper chamber having a fuel discharge port leading therefrom to the exterior of said body and said lower chamber having a steam discharge port of materially less diameter than said fuel discharge port and leading therefrom and merging with said fuel port.

2. A hydrocarbon burner of the character described, comprising a body having formed therein a pair of superposed chambers, the upper of said chambers being of greater diameter than the lower one and having a series of downwardly extending passages opening through the floor adjacent the wall thereof, said lower chamber having a radially extending series of relatively narrow passages leading therefrom, each opening into the lower end of a downwardly extending passage, and said body having a radially extending series of passages of larger diameter than said narrow passage, leading from the lower end of said vertical passages to the outside of said body and each in alignment with one of said narrow passages..

In testimony whereof, I affix my signature hereto.

WILLIAM D. STACEY.
